PATENTED FEB. 25, 1908.

C. T. & E. E. WILT.

OVERHEAD SUSPENDING MECHANISM FOR MOTOR DRIVEN TOOLS.

APPLICATION FILED AUG. 15, 1906.

UNITED STATES PATENT OFFICE.

CHARLES T. WILT AND ELMER E. WILT, OF CHICAGO, ILLINOIS, ASSIGNORS TO CHAS. T. WILT,
OF CHICAGO, ILLINOIS, A FIRM.

OVERHEAD SUSPENDING MECHANISM FOR MOTOR-DRIVEN TOOLS.

No. 880,059.

Specification of Letters Patent.

Patented Feb. 25, 1908.

Application filed August 15, 1906. Serial No. 330,703.

To all whom it may concern:

Be it known that we, CHARLES T. WILT and ELMER E. WILT, citizens of the United States, of Chicago, in the county of Cook and 5 State of Illinois, have invented certain new and useful Improvements in an Overhead Suspending Mechanism for Motor-Driven Tools; and we do hereby declare that the following is a full, clear, and exact description 10 thereof, reference being had to the accompanying drawings, and to the letters of reference marked thereon, which form a part of this specification.

This invention relates to improvements in 15 overhead supporting devices for manually applied engine driven tools such as electrical or pneumatically driven drills, chipping hammers and other tools designed to be held to their work by manual operation while 20 driven from a suitable motor or engine.

The invention relates to improvements in the holder which is so constructed and arranged that the engine and tool automatically assume a given or predetermined position 25 with the tool directed away from the work and the holder is formed to provide a casing into which the tool is swung when it assumes its inoperative position, thereby protecting the operator from injury by contact with the tool 30 in the event that the engine is not stopped or arrested.

The invention consists in the matters hereinafter set forth and more particularly pointed out in the appended claims.

35 In the drawings:—Figure 1 is a side elevation of the apparatus. Fig. 2 is an enlarged side elevation of the engine and its holder, showing in dotted lines a changed position of the engine and its tool. Fig. 3 is a front elevation of the parts shown in Fig. 2. Fig. 4 is a detail illustrating the pivotal connection of the holder with the engine casing. Fig. 5 is a swivel connection of the holder with its suspending cable. Fig. 6 is a transverse 40 section of one form of track for the tool supporting carriage, and illustrating the bearing wheel for the carriage. Fig. 7 is a detail section, taken on line 7—7 of Fig. 1. Fig. 8 is a detail section, taken on line 8—8 of Fig. 1.

45 As shown in the drawings, A designates, as a whole, an engine or motor for driving the tool and it may consist of an electrical or pneumatic motor.

50 B designates a tool consisting in the present instance of a drill which is fitted to a

50 chuck suitably connected with the driving shaft or rotor of the engine.

C designates, as a whole, the tool holder by which the tool and engine are directly suspended.

55 D designates an overhead crane or bracket from which the tool and its holder are suspended. Said crane or bracket may be made of various forms and is movably mounted so as to increase the field or range of work of the tool. As herein shown, it comprises a horizontal arm d from which the tool is suspended, a vertical member d¹ and a brace d². The said bracket is hinged to a suitable support E, which may consist of a post or the 60 wall of the building, so that it may be swung throughout a portion of a circle, it being in the present instance mounted to swing 180 degrees of a circle. To this end it is pivoted by means of trunnions d³ d³ at the upper and 65 lower ends of the vertical member thereof that has pivotal or rotative connection with studs e e projecting from the support E. The said engine and its holder are suspended from the horizontal arm of said crane or 70 bracket through the medium of a flexible cord or cable F which latter is suspended from a carriage G that is movably mounted in any suitable manner on the horizontal arm of the crane or bracket. Said carriage 75 is supported and moves, in the present instance, on a rail H affixed to the under side of the horizontal arm of the crane or bracket. In the present instance, said engine and 80 the tool are counterbalanced by a counterweight I that is suspended from the end of the cable F opposite that which is attached to the engine, and the cable is trained about suitable pulleys g g rotatively mounted in the carriage G. This arrangement permits the 85 engine and tool to be raised and lowered with the exertion of little power to bring it to a desired working level and little or no lifting power is required to hold the tool to its work. The carriage G is movable longitudinally on the track H of the horizontal arm of the crane thus permitting the suspended engine and tool to be accommodated to a wide range of work. In addition to the 90 two movements of the engine and tool described, the range of movement is further amplified by reason of said parts being suspended on a crane or bracket which swings horizontally throughout a part of a circle in the manner described.

Referring now to the construction of the engine holder and the means of supporting the engine thereon, these parts are made as follows: The said holder comprises a yoke 5 having two downwardly extending, laterally separated arms $c\ c$ which are apertured at their lower ends to receive studs c^1 extending laterally from opposite sides of the shell of the engine. In the present instance, the engine 10 is an electrical motor, and I have shown means for suspending the same whereby an ordinary electric motor, primarily designed to operate a fan or to perform other analogous work may be adapted for this use. To this end I may apply to the casing of the engine a metal band A^1 which, in the present instance, consists of a continuous piece that encircles the casing and is formed at its ends to provide lateral clamping lugs $a\ a$ through 15 apertures in which extends a clamping bolt a^1 by which the bend is clamped in place on the ring. A yielding strip made of rubber or the like may be interposed between the band and engine casing. If the engine be primarily 20 built for the purpose herein described, said lugs may be cast directly on the shell of the engine casing. The said yoke arms $c\ c$ of the holder are brought together above the engine to form two parallel members $c^2\ c^2$ 25 which are joined by an integral curved part c^3 at the top of the holder. The said holder is suspended from the cable F by means of an eye C^2 which may be attached in any suitable manner to the upper closed parts c^3 of 30 the holder. Desirably said eye is connected with the upper part of the holder by a swivel joint, which is more clearly illustrated in Fig. 5. The said swivel joint, in the present instance, embraces a shank c^4 extending downwardly from the eye, through a suitable aperture in the upper closed end of the suspending member of the holder and is provided with upper and lower collars or flanges $c^5\ c^6$, respectively, to hold the same vertically in 35 place. The construction is such that the shank of said eye is free to rotate in its bearing thereby facilitating the turning movement of the holder and the engine about a vertical axis. 40

A feature of my invention is comprised in a holder of this character wherein the engine is so mounted that it assumes a position to swing the tool upwardly in a vertical position, as indicated in dotted lines in Figs. 2 45 and 3, when the hand of the operator is released from the handle A^2 with which the engine casing is equipped. That is to say, said engine is so eccentrically loaded or overbalanced in its holder that when said handle 50 A^2 is released, the tool side of said engine swings upwardly to bring the tool to the position referred to.

As a further and separate improvement the said holder is so constructed as to provide a housing or casing into which the tool 55

B is moved when the engine assumes its inoperative position as described, thereby protecting the operator from accidentally bringing his hand or other part of his body into contact with the tool. In this manner 70 liability of serious accident is avoided in case the tool should continue its operation after the engine is released. A convenient construction and arrangement of such a protecting casing or housing is shown in the drawings and comprises, in combination with the parallel members $c^2\ c^2$ of the holder, guard members $c^7\ c^7$ which extend inwardly toward each other from the opposite edges and at 75 right angles to said members c^2 . Said guard members do not meet, thereby forming slots $c^8\ c^8$ through which the tool may swing into the housing or casing when the engine is released from the manual control of the operator. It will thus be seen that the tool is 80 brought to a position by reason of the overweight or eccentric loading of the engine in the holder, which minimizes liability of accident and that the operator is perfectly 85 protected from accident by reason of the tool swinging into the casing or housing referred to. If desired but one side of the casing or housing may be so slotted, but in practice it will be preferable to slot both sides thereof. 90

A form of track is herein provided which 95 is recommended for various reasons of advantages which will appear in the following description. The said track which I have herein shown comprises a tubular member H which is provided in its lower side with a slot h , and the carriage G is provided with hangers g^1 which extend upwardly through the slot of the tube into the interior thereof. Said hangers are provided within the tube with suitable bearings, preferably roller 100 bearings, to facilitate the travel of the carriage along the rail. As herein shown, the roller bearing for each hanger comprises two wheels $g^2\ g^2$ that are fixed to the opposite ends of a shaft g^3 which extends transversely 105 through a suitable bearing aperture in the hanger. Preferably the hanger is of such construction as to afford between the same and said shaft, seats for antifriction balls g^4 110 which reduces the rotative friction of said axles g^3 in the hangers. Preferably said wheels g^2 may be made with beveled or inclined peripheries to adapt the same to the cylindric inner wall of the rail. They also are desirably made of a non-resonant material 115 so as to minimize the noise incident to the wheels rolling along the rails. This form of rail is advantageous for the reason that it possesses great strength, by reason of its circular cross-section. Furthermore, the rail 120 constitutes a complete housing for the bearing members of the carriage thereby not only protecting said bearing members of the carriage from dust and dirt, but also avoiding the liability of the same passing over the 125 130

hand of a person who might grasp the rail during the use of the apparatus.

Any suitable means may be employed for fastening this form of rail to the horizontal arm of the crane or bracket. As herein shown, the said rail is fastened at its ends to said arm by means of plugs H^1 H^1 entering the ends of the rail, and said plugs are formed to provide flanges h^1 h^1 having apertures through which extend suitable fastening bolts or screws to fix the same to the underside of the horizontal arm of the crane. An intermediate support consisting of a suitable clasp H^2 partially encircling the tubular rail and likewise having a flange h^2 may be provided for supporting the rail intermediate its ends. The plugs of the end supporting devices are provided with lugs h^3 that enter the slot of the rail, whereby said rail is held from rotating.

The conductor wires J, if the engine be an electric motor, or the air pipes, if it be a pneumatic motor, may be disposed in any suitable manner, such as will not limit the application of the tool. As herein shown, said conductor wires lead from a socket which may be fixed in the support E, and from thence said wires are trained through suitable guide eyes along the horizontal arm of the crane and thence downwardly to the engine.

We claim as our invention:—

1. The combination with an overhead support, an engine supported therefrom provided with a tool connected with and driven from said engine, of a holder in which said engine is swingingly mounted, said engine being eccentrically loaded with respect to its swinging connection with the holder, whereby when released from manual control it assumes a position to direct the tool upwardly.

2. The combination with an overhead support and an engine and its tool suspended therefrom, of a holder in which said engine is swingingly mounted, a cable for suspending the holder from said overhead support, said engine being eccentrically loaded with re-

spect to its swinging connection with the holder whereby, when released from manual control, it assumes a position to direct the tool upwardly. 50

3. The combination with an overhead support and an engine and its directly driven tool, of a holder in which said engine is mounted comprising yoke arms extending on opposite sides of the engine casing, lugs extending from said engine casing and engaging bearing apertures in said yoke arms, and means for flexibly suspending said holder from the overhead support, said motor being eccentrically loaded whereby, upon release from manual control, it automatically assumes a position to direct the tool upwardly. 65

4. The combination with a tool holder and means for flexibly sustaining it from an overhead support, of an engine and its directly driven tool swingingly mounted in said holder, a housing or casing fixed to the holder, the motor being overweighted on the side thereof opposite to the tool relatively to the swinging axis whereby the engine is automatically swung to a position to move the tool into said housing when the engine is released from manual control. 70

5. The combination with an engine and its directly driven tool, of a holder in which said engine is swingingly mounted, means for flexibly sustaining the holder from an overhead support, said engine being eccentrically loaded whereby, when released from manual control, it assumes a position to swing the tool upwardly, and the holder being formed to provide a protecting housing into which said tool is swung. 80

In testimony, that we claim the foregoing as our invention we affix our signatures in the presence of two witnesses, this 11th day of August A. D. 1906.
